CLAIM

The ornamental design for a tubular positioning guide, substantially as shown and described.

DESCRIPTION

FIG. 1 is a front, perspective view of a tubular positioning guide in accordance with the present design;

FIG. 2 is rear, perspective view of the tubular positioning guide of FIG. 1;

FIG. 3 is a right, side view of the tubular positioning guide of FIG. 1;

FIG. 4 is a front view of the tubular positioning guide of FIG. 1;

FIG. 5 is a left, side view of the tubular positioning guide of FIG. 1;

FIG. 6 is a rear view of the tubular positioning guide of FIG. 1;

FIG. 7 is a bottom view of the tubular positioning guide of FIG. 1;

FIG. 8 is a top view the tubular positioning guide of FIG. 1; and,

FIG. 9 is a perspective view of the tubular positioning guide of FIG. 1, shown in environment.

The broken lines in the FIG. 2 and FIG. 6 views represent the bounds of the claimed design while the broken lines in the FIG. 9 view are directed to environment and are for illustrative purposes only; the broken lines form no part of the claimed design.
